A. GREENE.

Thill-Coupling.

No. 14,096.

Patented Jan 15, 1856.

UNITED STATES PATENT OFFICE.

ALLEN GREENE, OF PROVIDENCE, RHODE ISLAND.

MODE OF ATTACHING THILLS TO AXLES.

Specification of Letters Patent No. 14,096, dated January 15, 1856.

To all whom it may concern:

Be it known that I, ALLEN GREENE, of the city and county of Providence, in the State of Rhode Island, have invented a new and Improved Method of Attaching the Thills or Shafts of Carriages to the Axle; and I do hereby declare that the following is a full and exact description.

The nature of my invention consists in attaching the shaft or thill iron to a piece of leather, gutta percha, or other similar substance and then attaching the leather, gutta percha or other similar substance to the axle, as is shown by the drawing hereto annexed marked A, and upon which the shaft or thill iron is represented by the letters *a*, *a*, the leather, gutta percha, or other similar substance by the letters *b*, *b*, and the axle by the letters *c*, *c*.

What I claim is—

The use of the leather, gutta percha or other similar substance in attaching the thill or shaft to the axle.

The improvement is this:—It is more economical and safer than the attachment by shackle, now commonly in use; and it prevents entirely any rattle at the attachment aforesaid, which rattle is now a subject of general complaint, especially among those who use light carriages.

Providence, Dec. 13, 1855.

20

ALLEN GREENE.
